ALBERT E. KEPPLER, OF PHILADELPHIA, PENNSYLVANIA, ASSIGNOR TO BROWN & BAILEY COMPANY, A CORPORATION OF PENNSYLVANIA

PACKING AND DISPLAY BOX

Application filed April 9, 1928. Serial No. 268,526.

My invention relates to packing and display boxes, the principal object being to provide a foldable box having reinforced sides, ends and corners which may be constructed from a unitary blank of suitable material, the blank being cut out by a suitable die and the different parts thereof then folded and interlocked into proper relation to form the completed box. Complementary and interfitting boxes may be made, one being slightly larger and adapted to telescope with the other and form the cover therefor; when the contents of the box are to be displayed for sale purposes the larger box may be removed from the top and the smaller box, with the contents, placed therein.

My invention further includes all of the other various objects and novel features of design, construction and arrangement herein-after more definitely specified or described or which will be apparent from the accompanying drawings in which I have illustrated a preferred embodiment and some modifications thereof of my invention.

In said drawings, in which the same numerals designate like parts in the different figures, Fig. 1 is a plan view of the blank before the same is folded up to form the box, the points at which the blank is scored or weakened to facilitate the folding operation being indicated in dot and dash lines; Fig. 2 is a perspective view, in part, of the box before the ends are folded; Fig. 3 is a like view showing an intermediate step in the folding of the ends; Fig. 4 is a like view showing the next step; Fig. 5 is a longitudinal, fragmentary section showing the position of the parts before the last step in the folding; Fig. 6 is a perspective view of the box completely folded; Fig. 7 is a section on the lines 7—7 of Fig. 6; Fig. 8 is a plan view of one end of a modified form of blank, the points at which the blank is cut entirely through being indicated in full lines; Fig. 9 is a plan view of the other end of the blank shown in Fig. 8 with the inner side members folded upon the outer side members to which they are respectively attached; Fig. 10 is a plan view of one end of another modified form of blank and Fig. 11 is a plan view of the other end of the blank

shown in Fig. 10 with the inner side and corner members folded inwardly.

The blank may be cut from cardboard, paper stock or other suitable material, by a die at a single operation, the preferred form 55 of blank being shown in Fig. 1 in which the bottom of the box is designated at 1, the outer side members at 2, 2, the inner side members at 3, 3, the outer end members at 4, 4, the inner end members at 5, 5, narrow strips or tabs 60 at 6, 6, tapering tongues at 7, 7, 7, 7, being end extensions of the inner sides 5, 5 and adapted to fit snugly within cutouts 8, 8, 8, 8 in the inner sides 3, 3 and lock the parts forming the folded box, and corner members 9, 9, 9, 9 65 connecting with sides 2 and the ends 4 and foldable on the scores 10, 11 and 12 to form gussets.

In forming the box from the blank, the inner sides 3, 3 are preferably first folded on the 70 scores 13, 13 so as to lie upon the inner surfaces of the adjacent outer sides 2, 2 and are preferably secured thereto by an adhesive such as glue. While I have shown the inner sides 3, 3 as being of substantially equal width 75 with the outer sides 2, 2 (excepting the cutouts 8, 8) they may be of less width if desired. This first step in the folding operation is illustrated in Fig. 9.

The pairs of side members, secured together 80 as aforesaid, together with the corner members 9, are then erected by folding about the scores 14 and 10, respectively, to positions substantially at right angles with the bottom 1, as shown in Fig. 2, following which outer 85 end members 4, 4 are folded on the scores 15 into positions at right angles to the bottom 1 whereupon the box will take the form, at both ends, as shown in Fig. 4. I have illustrated in Fig. 3 an intermediate step in this 90 last folding operation from which it will be seen that as the folding of the end members 4 progresses the corner members 9 will fold inwardly on the scores 10, 11 and 12 and when the end members 4 are positioned at right 95 angles to the bottom 1, the two triangular portions forming the corner members 9 will be brought into parallel relation bearing against the inner surfaces of the end members 4 and forming gussets.

After the box has been partially formed as shown in Fig. 4, the inner ends 5 are folded on the scores 16, 16 so that they, and the tabs 6 attached thereto, will lie parallel to the bottom 1, the tongues 7 having been folded about the scores 17 at right angles to the inner sides 5 of which they form extensions and extending within the box as shown in Fig. 5.

The inner end members 5, 5 are then again folded on the scores 16 into the interior of the box and in parallel relation with the outer end members 4 whereupon the tabs 6 will bend about the scores 18 and, due to the inherent elasticity of the cardboard, will bear against the bottom 1 of the box and be effectively held against accidental dislodgment; the tongues 7 will spring into the cutouts 8 and form an efficient lock to hold the parts of the box in assembled relation as shown in Figs. 6 and 7. It will be evident that the box may be restored, if desired, to blank form by reversing the folding steps.

In the modification shown in Figs. 8 and 9 the corner members 9 are shown as separated from the outer end members 4 and secured only to the outer side members 2 and in the modification shown in Figs. 10 and 11 I have shown the corner members secured to the outer end members 4 by wire stitches or staples although other suitable securing means may be used, if desired. I have found boxes embodying these modifications to be satisfactory but my preferred embodiment is that illustrated in Figs. 1 to 7.

Inasmuch as my improved box may be made from a single blank of material, it may be manufactured at a maximum economy of labor and material; it also will withstand rough handling and possesses great durability by reason of its reinforced construction and the secure locking means which I have provided. Additionally, it will be observed the blanks may be shipped in flat form to the user who can readily fold them into box form, this resulting in a very considerable saving in shipping expense.

While I have herein described and illustrated with considerable particularity a preferred embodiment of my invention and some modifications, I do not thereby desire or intend to in any manner limit myself specifically thereto as the design, construction and arrangement of the various parts may be modified if desired from the precise forms to which I have referred without departing from the spirit and scope of the invention as defined in the appended claim.

Having thus described my invention, I claim and desire to protect by Letters Patent of the United States:

A box formed from a single blank of foldable material and comprising a bottom, outer sides, inner sides provided with cutouts at each end, outer ends, inner ends having tongue members extending from each end

thereof and adapted to fit snugly within said cutouts, said tongue members extending to the bottom of the box when in interlocked relation with the cutouts of the inner sides, gusset members connected with the ends of said outer sides and outer end members and lying between each pair of inner and outer ends and tabs extending from said inner end members adapted to be bent and bear against the bottom of the box and also extending entirely across the latter to retain the tongues in interlocked relation with the inner sides of the box.

In witness whereof I have hereunto set my hand this 7th day of April, 1928.

ALBERT E. KEPPLER.
